UNITED STATES PATENT OFFICE

EARL T. BENNINGTON, OF CLEVELAND HEIGHTS, OHIO, ASSIGNOR TO THE CLEVELAND CRANE & ENGINEERING COMPANY, OF WICKLIFFE, OHIO, A CORPORATION OF OHIO

CRANE

Application filed June 2, 1927, Serial No. 196,124. Renewed January 7, 1929.

This invention relates to cranes of the bridge type and has for its object to provide a traveling bridge of wide span which is of relatively light construction and which is adapted to be supported upon ordinary monorail tracks.

A further object is to provide a wide span bridge crane in which the bridge is so mounted that a minimum of frictional resistance is offered to its travel along its supporting runway and in which the bridge is adapted to be moved along its run-way manually by pushing against the bridge at any point along the length thereof so that a man on the ground, by pushing on a part of the hoist trolley or on loads suspended from the trolley, may move the bridge along its run-way or the trolley along the bridge, and walk with the load in any desired direction and to any point within the area covered by the crane.

With the above and other objects in view, the invention may be said to comprise a structure as illustrated in the accompanying drawings hereinafter described and particularly set forth in the appended claims together with such variations and modifications thereof as will be apparent to one skilled in the art to which the invention appertains.

Reference should be had to the accompanying drawings forming a part of this specification in which:

Fig. 1 is a transverse vertical section through the supporting run-way showing the bridge and hoist trolley in side elevation;

Fig. 2 is a transverse section through the bridge taken on the line indicated at 2-2 in Fig 1; and

Fig. 3 is a diagrammatic plan view illustrating on an exaggerated scale the lateral flexure of the supporting rails when the bridge is being propelled along its run-way by pressure applied to one end thereof.

As illustrated in the accompanying drawings the crane run-way is composed of a series 45 of parallel monorail tracks 1, each composed

of road rails T-shaped in cross section and provided with oppositely extending flanges upon which the supporting wheels run. The monorail tracks 1 are flexibly suspended at intervals along their length to permit lateral flexure, the suspension devices consisting of flexible hinges 2 attached to the lower ends of rods 3 which have ball heads 4 seated in socket supports 5 attached to a suitable overhead support such as the overhead beams or girders of a building. Suspension rods 3 are adapted to swing in any direction permitting portions of the monorail tracks to be deflected laterally during travel of the bridge along the run-way.

As shown herein, the bridge consists of a girder 6 extending transversely beneath the supporting tracks 1, the girder 6 consisting of an upper T-shaped section of structural steel and a lower section 8 in the form of a standard monorail which has its web welded to the web of the upper section 7. In order to lighten the girder, portions of the web of the upper section 7 are cut away, as indicated at 9 in Fig. 1, and the webs joining the section 7 to the rail 8 are made in the spaces between the cut-away portions 9. For supporting the girder 6 upon the monorail tracks 1 cross bars 10 are rigidly attached to the top of the girder at points along the length thereof corresponding to the positions of the supporting tracks and the portions of these bars extending across the top of the girder have spaced side members 11 which are adapted to receive the supporting rails 1 between them so that the girder may travel beneath the supporting tracks with its top immediately beneath the bottoms of the supporting rails.

Cross bars 10 project on opposite sides of the girder 6 and are provided with downwardly offset end portions 12 on which are swiveled load bars 13 which are connected to the ends of the cross bars 10 by means of vertical and horizontal pivots 14 and 15. Wheel carrying frames 16 are connected by swivels 17 to the

opposite ends of the load bars 13 and carry wheels 18 which travel upon opposite flanges of the supporting tracks 1.

Mounted to travel upon the monorail section 8 of the girder there is a hoist trolley 19 which has wheels 20 traveling upon the opposite flanges of the rail 8, the trolley being provided with the usual hoist drum and motor by means of which a hoist cable 21 may be wound or unwound to raise or lower a load suspended therefrom. Current may be supplied to the hoist motor from conductor rails 23 extending along one of the supporting rails 1 through current collectors 24 carried by one of the steel frames from which the bridge is supported and having connections to conductor rails 25 extending along opposite sides of the girder 6 which deliver current to collectors 26 on the trolley. The hoist motor may be controlled by a pair of push buttons 27 on a rigid depending handle 28 attached to the load bar of the trolley.

By providing one or more supporting tracks intermediate the tracks supporting the ends of the bridge, the bridge girder may be of much lighter construction for a crane of a given capacity. The flexible suspension of the supporting tracks is an important feature of the present invention since it permits the bridge to be readily moved along the run-way by pressure applied at any point along the length of the bridge. This enables a man on the ground, by pushing on the rigid handle 28 of the trolley or upon a load suspended by the hoist cable 21, to move the bridge along its run-way regardless of the position of the trolley on the bridge. As diagrammatically illustrated in Fig. 3, the bridge, at the end to which pressure is applied, has a tendency to run ahead of the opposite end on the run-way and this would ordinarily create such a frictional resistance to movement that it would be impossible, with a bridge of long span, for a man on the ground to propel the bridge along its run-way.

With cranes constructed in accordance with the present invention, it has been found that very little pressure is required even at the end of the bridge to propel the bridge along its run-way. The flexible suspension of the supporting tracks 1 permits the end of the bridge, to which pressure is applied, to run slightly ahead of the opposite end and by reason of the fact that the cross bars 10 are rigidly connected to the girder, movement of one end of the girder ahead of the other will cause a lateral movement of the tracks, as illustrated in Fig. 3. This bending is in reality very slight, the showing in Fig. 3 being exaggerated for the purposes of illustration. The tracks when laterally moved tend to return to their normal straight position and exert pressure through the cross bars 10, tending to restore the girder to a position at right angles to the tracks and to swing the lagging

end forwardly to a position even with the end which is being pushed. The swivel mounting of the wheel carrying members is important since it allows the wheels to follow without binding any lateral movements of the track produced by one end of the girder running ahead of the other. Whenever pressure applied to the end of the girder is momentarily released, the tracks return to their straight position and the lagging end of the girder is swung forward until the girder is again at right angles to the supporting tracks. The flexibly suspended supporting tracks co-operate with the swiveled supporting wheels and rigid wheel carrying cross bars of the girder to permit the girder to be moved along its supporting run-way with a minimum of frictional resistance to such movement. An operator on the ground, by simply pushing against the handle 28 or against the load carried by the hoist cable 21, may move the trolley along the track 8 of the bridge or may move the bridge bodily along its run-way and by the combination of these movements can cause the load to travel in any direction desired and to any point within the area covered by the crane.

Having thus described my invention, I claim:

1. A bridge crane having a series of three or more parallel supporting tracks each flexibly suspended at intervals along its length so as to be capable of limited lateral movement, a trolley supporting bridge member extending transversely of said tracks, and means for supporting said bridge member from said tracks comprising members projecting laterally to opposite sides of the bridge member and rigidly secured thereto, members swiveled to said projecting members on opposite sides of the bridge member and wheels carried by said swiveled members and adapted to travel on said tracks.

2. A bridge crane having a series of three or more parallel supporting tracks each flexibly suspended at intervals along its length so as to be capable of limited lateral movement, a bridge mounted to travel on said tracks and comprising a girder extending transversely of the tracks and provided with oppositely extending flanges forming a trolley track, cross members rigidly connected to the girder and extending across the top thereof adjacent the supporting tracks, members swiveled upon opposite ends of each of the cross members and wheels carried by said swiveled members adapted to travel on the supporting tracks.

3. A bridge crane having a series of three or more parallel supporting tracks each flexibly suspended at intervals along its length so as to be capable of limited lateral movement, a bridge extending transversely of said tracks, and means for supporting said bridge so that the same may travel along the tracks,

1 said means comprising a plurality of members rigidly connected to said bridge and extending on opposite sides thereof in substantially the same direction as the tracks, two of said members being located adjacent opposite ends of the bridge and the remaining of said members being arranged intermediate the first two members, and wheels associated with said members adapted to travel on said tracks.

10 In testimony whereof, I hereunto affix my signature.

EARL T. BENNINGTON.
